UNITED STATES PATENT OFFICE

2,631,221

HIGH-FREQUENCY ELECTRICAL HEATING APPARATUS

John G. Littell, Florham Park, N. J., assignor to
Krementz & Company, Newark, N. J., a corpora-
tion of New Jersey

Application March 26, 1951, Serial No. 217,566

6 Claims. (Cl. 219—47)

1

This invention relates to a circuit for heating small non-ferrous metal devices such as are used in the jewelry trade. In general this present invention relates to an improvement over Patent No. 2,493,269 issued January 3, 1950, to Harrison D. Simpson. This patent sets forth in considerable detail the use of high frequency apparatus for the purpose just described. The patent also points out in considerable detail the prior art methods which had been in use, or at least tried out prior to the filing of the application for said patent. In view of these disclosures it does not seem necessary to discuss the prior art set forth in the patent, except to mention that the present application is directed to improvements upon the apparatus disclosed in the Simpson patent.

In the use of the Simpson patent, there is a difference in potential of as much as 3500 volts between the primary and secondary windings of the grid transformer. Because these are of necessity in close physical proximity to obtain close coupling, the high voltage often arced across between these windings, causing damage to the insulation of the transformer which put it out of use until repairs would be made. Apparently this was partly due to the out of phase relation between the primary and secondary voltages assisted by transient peaks caused by opening and closing of the switch controlling the plate current as each piece was inserted in the work coil. Several methods of constructing the grid transformer of said patent were tried in order to increase the period of time during which the apparatus could be maintained in operating condition but none of these methods were found to be perfectly satisfactory.

It is therefore the principal object of my present invention to provide a grid transformer connected in the circuit in such a way as to eliminate all the trouble experienced with the apparatus of said patent. My new arrangement comprises an auto-transformer having the grid of the vacuum tube oscillator connected to one end of the transformer winding while the other end is connected to the anode of the oscillator tube, with a ground connection made at the adjustable contact which is an adjunct of an auto-transformer. This provides an arrangement in which one portion of the transformer is connected to the anode of the oscillator tube while the other portion is connected to the grid of the tube, the relation between the two portions being adjustable by reason of the movable contact which in effect separates the transformer into primary and secondary windings with the primary being connected to the

plate of the tube and the secondary to the grid. With this arrangement the voltage ratio of the two coils can be adjusted to produce an optimum of grid feed voltage and hence maximum efficiency.

Furthermore, because the auto-transformer is a single layer coil the difference in potential between any two conductors that are in close physical proximity is reduced from 3500 volts to about 10 350 volts and arcing is effectively eliminated.

I have found that highly satisfactory results can be obtained by using an auto-transformer the helical or single layer coil of which is made up of $\frac{1}{8}$ " copper tubing and having an outside diameter of the turns of $6\frac{1}{2}$ " and a winding length of approximately $2\frac{1}{4}$ " using approximately ten or eleven turns. The movable contact should be 15 preferably arranged so that it may be readily moved to vary the relationship between the primary and the secondary sections.

The circuit arrangement with which this grid transformer is used is in general the same as that shown in the Simpson patent, however, there have been introduced certain circuit changes as can 20 readily be seen by referring to the single figure of the drawing. In the circuit showing my improvement is a step-up transformer 1 having a primary P which may have an ammeter A in its circuit. The secondary S is connected to two 25 rectifier tubes 2 and 3 which as shown are of the gas type. Filaments of the tubes 2 and 3 are connected to the secondary 6 of the transformer 30 4 having a primary 5 connected to the same source of supply as the primary P of the transformer 1. The center tap of the winding 6 is 35 joined by a conductor 7 through a radio frequency choke coil 8 to keep oscillations from the high frequency oscillating tube T out of the source of direct current coming from the tubes 2 and 3. The tube T has a plate or anode 9, a grid 10 and filament 11 the latter of which is supplied with 40 current from a transformer 12 having a primary 13 and secondary 14. Connected to the anode of the plate 9 is a blocking condenser 15 to keep direct current out of the resonant circuit which 45 includes a tank condenser 16.

The heating coil 17 is composed of very few number turns in the order of two or three which resonate at a frequency of a few megacycles. 50 By using a heater of such few turns, a device such as a piece of jewelry can be readily inserted into heating position and soldered during the matter of two or three seconds of the heating operation. This heating coil preferably is made of copper tubing for passing cooling fluid therethrough.

The primary portion of the auto-transformer AT is connected in parallel across the condenser 16 and the heating coil 17. One end of the primary is connected to the tube T through the blocking condenser 15, while the secondary of the transformer has its free end 20 connected through a parallel arrangement of a grid bias resistor 24 and by-pass condenser 25 to a parasitic suppressor composed of resistance 22 and inductance 21 arranged in parallel relationship and connected to the grid 10. The movable contact 19 of the transformer along with one side of the condenser 16 and one end of the heating coil 17 are connected to the ground. The center of the winding 14 of the filament transformer 12 is also grounded thereby giving a feedback circuit to the filament of the tube T. With this arrangement the connections from the secondary of the transformer to the grid are in substantially a series circuit made up of the parts as just described. I have found with this arrangement which has been used over quite a period of time that troubles I have referred to have been overcome and overall improvement in efficiency of approximately three per-cent to five per-cent have been obtained over the prior arrangement. Furthermore, the cost of the grid transformer has been materially reduced and much time is saved in the operation of the system for the reasons heretofore explained.

I claim:

1. Means for heating metal parts including a high frequency oscillator vacuum tube with means for feeding direct current to the plate of the tube, a tank condenser connected in the output circuit of the tube, a heating coil connected in parallel with the tank condenser and composed of few turns to facilitate the handling operation of the parts to be inserted into the space within said turns for heating them, an helical single layer coil having few turns of large diameter with a movable tap connected to that side of the tank condenser opposite to the side that is connected to said tube plate and also one end of the auto transformer being operatively connected to said output circuit of the tube along with the condenser while the opposite end of the transformer is operatively connected to the grid of the tube, and a blocking condenser connected between the output of said tube and said tank condenser.

2. Means for heating metal parts as set forth in claim 1 further defined in that the connections to the grid of the tube includes a parasitic suppressor with at least a condenser in series with the suppressor.

3. Means for heating metal parts, including a high frequency triode tube and means for heating its filament, means for supplying high voltage direct current to the plate of said tube through a radio frequency choke, a blocking condenser to keep high voltage direct current away from the oscillator circuit, a heating coil of few turns, a tank condenser in parallel with said heating coil, both said heating coil and said tank con-

denser being connected between the plate of the triode tube and ground through the blocking condenser, an helical single layer coil having few turns of large diameter having an adjustable contact and one portion between said adjustable contact and one end, connected in parallel with the tank condenser and heating coil while the other portion is operatively connected to the grid of said tube to provide a feedback voltage therefor.

5. Means for heating metal parts as set forth in claim 3 further defined in that said feedback voltage to the grid is supplied through a grid bias resistor from the filament and a grid condenser connected to the last mentioned portion of the auto transformer.

6. Means for heating metal parts including a high frequency oscillator tube with means for feeding current to the plate of the tube, a tank condenser connected in the output circuit of the tube, a heating coil connected in parallel with the tank condenser and composed of a few turns to facilitate the handling operation of the parts to be inserted into the space within said turns for heating them, an helical single layer coil having few turns of relatively large diameter and an adjustable tap, said coil having its primary end connected in parallel with the tank condenser and the heating coil and the free end 20 of the secondary operatively connected to the grid of the tube to cause the same to deliver a high frequency current to the heating coil that will produce high heating in a matter of a very few seconds, and a blocking condenser to keep 25 high voltage direct current away from the resonant circuit.

7. Means for heating metal parts including a grid-controlled vacuum tube with means for feeding plate current and filament current to said tube, connected as a high frequency oscillator with a tank circuit in the output circuit of said tube comprising a condenser in parallel with a heating coil composed of few turns to facilitate handling of the work within said coil for heating 40 the work, means for producing oscillation in said circuit including an helical single layer coil in parallel with said tank circuit with one end of said helical coil connected to said tank condenser and a movable tap connected to said filament and with the other end of said coil connected through a bias resistor and grid condenser to the grid, and a blocking condenser between the output of 45 the tube and said tank condenser.
